UNITED STATES PATENT OFFICE.

WILLIAM THOS. HOGG AND LYNNE THOMAS RAND, OF UNITY, MAINE.

HYDRAULIC PRESS.

1,185,799.

Specification of Letters Patent.

Patented June 6, 1916.

Application filed September 15, 1914. Serial No. 861,862.

To all whom it may concern:

Be it known that we, WILLIAM THOS. HOGG and LYNNE T. RAND, citizens of the United States, residing at Unity, in the 5 county of Waldo, State of Maine, have invented a new and useful Hydraulic Press, of which the following is a specification.

The present invention relates to improvements in hydraulic presses, especially designed for straightening shafting, placing on or removing pulleys or driving gears from shafting or in fact working upon anything where heavy or rapid blows would endanger the mechanism.

15 The object of the present invention is the provision of automatic means which will automatically release the pressure at the rear of the piston should the same become excessive and tend to cause the piston to 20 drive the head off of the cylinder.

With the foregoing and other objects in view which will appear as the description proceeds, the invention resides in the combination and arrangement of parts and in 25 the details of construction hereinafter described and claimed, it being understood that changes in the precise embodiment of the invention herein disclosed can be made within the scope of what is claimed without departing from the spirit of the invention.

In the drawings—Figure 1 is a vertical longitudinal sectional view through the cylinder of the press showing the means for 35 automatically releasing the pressure. Fig. 2 is an enlarged detail view of the automatic discharge member of the casing. Fig. 3 is a front elevation of the lever supporting yoke and the automatic releasing mechanism. Fig. 4 is a detail view of the valve 40 and the stem.

Referring to the drawings, the numeral 1 designates the cylinder which is provided with the flange 2 at the open end thereof, 45 the cylinder adjacent the flange being adapted to be surrounded by the two members 3 and 4 which constitute a bracing and supporting yoke for the open end of the cylinder.

50 The open end of the cylinder 1 is sealed by the plate or head 16, the same being attached thereto by means of the bolts 16' which are of such a strength as to permit of the breaking of the bolts under undue strain rather than the fracture of the head 16. This head 16 is provided with the stuffing

box 17, in which is mounted the plunger 18 whose rear end is reduced and threaded as at 19 to engage and attach it to the piston head 20. This piston head 20 is a cylindrical disk composed of metal, and attached to the opposite faces thereof and extending to engage the inner wall of the cylinder 1, are the two flexible gaskets 21 and 22, which are preferably made of leather.

Provided at the rear end and concentrically of the cylinder 1 is the pressure fluid directing port 23, which has led there-to, the pipe 24 while connected in the disk or head 16 are two pressure fluid directing 60 pipes 25 and 25'. By this means, the piston 20 may be properly moved either to push the plunger when driving pulleys or gears upon the shaft or to pull the plunger to assist in removing the same from the shaft.

In order to provide a means for automatically releasing the pressure at the rear of the piston 20 when the plunger 18 is being moved from left to right as viewed in Fig. 1, and thereby prevent the plunger from 70 "blowing" the head 16 under great pressure, the relief port 26 is formed in the bottom intermediate of the ends of the cylinder 1, and has attached thereto, the discharge pipe 27. This pipe 27 is intersected by the valve 75 casing 28, in which is mounted for reciprocation, the valve 29 provided with the intermediate port 30. The parts 27—28 provide a cruciform member, one portion of which is connected to the cylinder and the other portion of which carries the valve therein. This valve as shown in Fig. 4, is a plunger 80 valve and is connected by means of the stem 31 so that the same may be properly recipro-cated, an adjusting collar 32 being disposed 85 upon the stem 31 and being acted upon by the spring 33 whose inner end abuts the ad-jacent end of the valve casing to normally hold the valve 29 in the position, as shown in Fig. 1, with the port 30 out of registration 90 with the discharge pipe 27. The outer end of the stem 31 is connected to one end of the lever 34, which is pivoted intermediate of its ends to the frame 35 attached to the disk 16, the opposite end 36 of the lever being dis-95 posed to be engaged by the head 37 of the stem 38, which is mounted through the bore 39 of the disk 16 and is provided with the head 40 which is disposed in the path to be engaged by the piston 20 when the same is 100 moved from left to right, as shown in Fig. 1, and before the piston 20 can engage or

abut the inner face of the disk 16 to injure or remove the same.

What is claimed is:

1. A hydraulic press including a cylinder having a head at one end and an inlet port at its other end, a piston in the cylinder having a piston rod working through said head, a discharge pipe connected to the cylinder between the ends thereof, a valve normally closing said pipe, and means for opening said valve including a stem slidable through said head and projecting into the path of the piston to be operated thereby.
2. A hydraulic press including a cylinder having a head at one end and an inlet port at its other end, a piston in the cylinder hav-

ing a piston rod working through said head, a cruciform discharge member having one portion attached to the cylinder between the ends thereof, a valve slidable in the other portion of said member and having an aperture to be brought into alignment with the first mentioned portion, a lever pivotally connected with said head, said valve having a stem pivoted to said lever, and a stem slideable through said head and pivoted to the lever to be operated by the piston.

In testimony that we claim the foregoing as our own, we have hereto affixed our signatures.

WILLIAM THOS. HOGG.
LYNNE THOMAS RAND.
